ROAD GRADER WITH TILTABLE WHEELS

Edward C. Gledhill, Galion, Ohio

Application October 22, 1948, Serial No. 55,901

1 Claim. (Cl. 37—157)

1

This invention relates to road graders of the leaning wheel type.

An object of this invention is to provide in a road grader an improved axle having oppositely inclined wheel spindles fixed to the outer ends thereof, the axle being rotatably adjustable so that the angle of inclination can be varied while the machine is in motion.

Another object of this invention is to provide in a road grader an improved axle structure embodying oppositely inclined spindles fixed to the outer ends thereof, and an operator for each axle whereby the latter may be rotatably adjusted while the machine is either stationary or moving.

With a road grader embodying this invention the wheels can be tilted in a direction to take up the side thrust, and/or turned with the same controls so that the front wheels of the grader will move to and maintain an offset position from the tractor pulling the grader so that the tractor element may be maintained on hard ground with the grader moving over the soft ground being graded which may be either level or inclined relative to the hard surface, and that the rear wheels of the grader can be offset from the front wheels of the grader so that these rear wheels can be turned to avoid running into the outer bank or the windrow being formed by the trailing edge of the grader blade.

With the above and other objects in view, my invention consists in the arrangement, combination and details of construction disclosed in the drawings and specification, and then more particularly pointed out in the appended claim.

In the drawings,

Figure 1 is a detail side elevation, partly broken away and in section, of a road grader constructed according to an embodiment of this invention,

Figure 2 is a fragmentary front elevation of the device,

Figure 3 is a fragmentary sectional view taken on the line 3—3 of Figure 2,

Figure 4 is a fragmentary sectional view taken on the line 4—4 of Figure 2,

Figure 5 is a fragmentary vertical section of the rear portion of this device,

Figure 6 is a detail front elevation, partly broken away and in section, of one of the axles,

Figure 7 is a plan view of the axles shown in Figure 6 with the worm gear removed,

Figure 8 is a fragmentary sectional view taken on the line 8—8 of Figure 5,

Figure 9 is a fragmentary sectional view taken substantially on the line 9—9 of Figure 3,

2

Figure 10 is a fragmentary sectional view taken on the line 10—10 of Figure 3.

Figure 11 is a fragmentary sectional view taken on the line 11—11 of Figure 10,

Figure 12 is a fragmentary sectional view taken on the line 12—12 of Figure 1,

Figure 13 is a fragmentary sectional view taken on the line 13—13 of Figure 12,

Figure 14 is a fragmentary front elevation, partly in section, and on an enlarged scale, of the bearing supporting the front axle.

Referring to the drawings, the numeral 20 designates generally a frame structure for a road grader which is formed with an intermediate body portion 21, a downwardly offset front portion 22, and a downwardly offset rear portion 23. The rear portion 23 is offset downwardly a substantial distance from the front portion 22.

A scraper blade 24 is adjustably supported from the frame 20, being mounted on a vertically adjustable supporting means 25, and the blade 24 is adapted to be adjusted not only up and down but also angularly, with respect to the line of travel. A front axle 26 is disposed at the front portion of the frame and in the present instance the front axle 26 is square in cross section and is formed with round intermediate portions 27 about which detachable bearings 28 are adapted to engage.

The bearings 28 include an upper bearing member 29 and a lower or cap bearing member 30 with the bearing members 29 and 30 secured together by fastening means 31. The upper bearing member 29 is formed with an upwardly and inwardly inclined arm 32 to which the divergent side 33 of a substantially V-shaped bolster 33b is adapted to be secured by fastening means 34.

The bolster 33b is formed with a horizontal or flat upper portion 35 to which is secured a fifth wheel 36 engageable with a bearing plate 37 which is fixed to the forward end of the frame 20. The bolster 33b also has fixed to the horizontal portion 35 thereof a hollow stud or pivot member 38 and the pivot member 38 has a nut 39 mounted on the upper end thereof.

The frame 20 also has secured to the rear thereof a rear axle 40 which is similar to the front axle 26 and is journaled to the frame 20 by bearings 41. The two axles 26 and 40 are of like construction and each has secured to the opposite ends thereof a pair of parallel spindles 42 which are inclined to the longitudinal axis of the axle 26 and are oppositely inclined to each other.

The spindle 42 has fixed thereto a pair of plates

43 and the plates 43 are fixed to the axle 26 by means of fastening members 44. The front axle 26 has mounted thereon a worm gear 45 which is disposed in substantially the center of the axle between the ends thereof, the worm gear 45 being formed with a square or polygonal bore 46 so that the worm gear will be non-rotatable with respect to the axle 26.

A worm 47 is adapted to mesh with the worm gear 45 and the worm 47 has fixed thereto a shaft 48 which is connected with a vertical shaft 49 extending through the pivot member 38 by means of a universal joint 50. The vertical shaft 49 is connected with an inclined extensible shaft 51 by means of a universal joint 52 and the extensible shaft 51 which is inclined upwardly and rearwardly is connected to an operating shaft or rod 53 by means of a universal joint 54. The rod or shaft 53 is journaled in the bearing 55 supported from the frame 20 by supporting bars 56. The worm gear 45 and the worm 47 are encased or enclosed in a split housing generally designated as 57 which is formed of upper and lower complementary housing members 58 and 59, each formed with confronting ears of flanges 61 and 62 respectively, which are connected together by fastening means 63.

The housing 57 is held against rotary movement by means of a substantially V-shaped brace 64 which is secured to the divergent sides of the bolster 33 and is secured to the rear flanges of the housing 57 by means of a bolt 65.

As shown in Figure 8, the worm gear 45 is formed with bosses 66 at the opposite ends thereof of which rotatably project through openings 67 formed in the sides of the housing 57. The rear axle 40 is adapted to be rotatably adjusted by means of a worm and worm gear assembly similar to that shown in Figure 4 with the assembly encased in a housing 57a which is held against rotation by means of a bolt 68 which extends through an ear 69 carried by a rear frame plate 70 secured to the frame 20. The worm shaft 71 is substantially longer than the worm shaft 48 and extends vertically upwardly through a platform 72 secured across the rear of the frame 20 and the shaft 71 at its upper end extends through a plate 73 supported above the platform 72 by a pair of supporting bars 74. The shaft 71 at its upper end has secured thereto a hand wheel 75 so that the rear axle 40 may be conveniently adjusted by a person standing on the platform 72.

In the use and operation of this device, the grader is adapted to be secured to the tractor device and the means of attachment for securing the grader to the tractor may include a draw-bar 83 connected to the plate 36 so that the grader may move along a line of travel laterally of the travel of the tractor. In this manner the grader may be moved over relatively soft ground with the tractor on relatively hard ground.

The wheels 82 which are rotatably mounted on the spindle 42 are inclined to the vertical in a direction whereby the wheels 82 will take up

the lateral thrust imposed on the grader by engagement of the scraper blade 24 with the ground. As viewed in Figure 2, the scraper blade will be inclined to effect a thrust to the right and the wheels 82 will thereby be inclined upwardly and to the left. Where the thrust is opposite from that shown in Figure 2, each axle 26 and 40 is rotated through substantially 180° so that the wheels will be inclined in the opposite direction.

10 The rotation of axle 26 is effected by rotating operating member 53 which will rotate worm 47 and worm gear 45. The rear axle 40 is rotated either clockwise or counter-clockwise in the same manner by rotation of the worm shaft 71 by turning of hand wheel 75.

I do not mean to confine myself to the exact details of construction herein disclosed, but claim all variations falling within the purview of the appended claim.

20 I claim:

A road grader comprising, a frame, a yoke rotatably carried by said frame, a scraping blade carried by said frame, a front axle carried by said yoke, a rear axle carried by said frame, 25 bearings rotatably supporting said axles adjacent the opposite ends thereof, a worm gear non-rotatably mounted on the center of each axle, a housing surrounding said worm gear, a worm journaled in said housing meshing with said 30 worm gear, means for holding each housing in a selected position relative to said frame, one of said means comprising a V-brace having its ends secured to opposite intermediate portions of the legs of said yoke, a bolt carried by said housing 35 extending through the apex of said brace, means threadably engaging said brace and movable therealong for connecting said bolt to said brace, the other of said means comprising a bearing bracket bolted on said frame, complementary 40 threaded apertured flanges formed on said second housing, means for adjustably holding said last mentioned means against rotation comprising a bolt extending through said apertured flanges and said bracket, means comprising hand 45 wheels remote from each of said worms, for selectively rotating each worm to rotate its associated axle, brackets carried by each end of each axle, the brackets at the opposite ends of each axle being inclined in the same plane at equal 50 opposite inclinations, spindles fixedly secured in each bracket and wheels carried by each spindle, whereby each pair of wheels may be inclined in either direction in both vertical and horizontal planes independently of the other pair.

55 EDWARD C. GLEDHILL.
